PUNCH RETAINER

Ferdinand Ziganek, Detroit, Mich.

Application May 13, 1937, Serial No. 142,451

2 Claims. (Cl. 279—76)

This invention relates to punching mechanisms and more particularly to an improved punch or work engaging member and a retaining means therefor.

An object of this invention is to provide in combination a work engaging member in the form of a punch or button die and a retaining means therefor so that the work engaging member may be firmly held in the retaining means 10 or block and, at the same time, so held that the work engaging member may be readily released when it is desired to replace or change such member.

Another object of this invention is to provide a relatively simple punch or work engaging member and the retaining means therefor which will not readily get out of order and which is so constructed that the punch or work engaging member will be held when in operative position in a predetermined position with respect to the retaining means so that the operating portion of the work engaging member will be disposed in the same position with respect to its complementary work engaging member at all times.

This invention is an improvement over the punch retaining means and work engaging member disclosed in my co-pending application, filed concurrently herewith.

With the foregoing and other objects in view, the invention will be more fully described hereinafter, and will be more particularly pointed out in the claims appended hereto.

In the drawing, wherein like symbols refer to like or corresponding parts throughout the several views,

Figure 1 is a top plan of the retaining block or the work engaging member.

Figure 2 is a vertical section partly in detail of the retaining means with a punch mounted therein.

Figure 3 is a sectional view taken on the line 3—3 of Figure 2.

Figure 4 is a fragmentary side elevation of the shank of the punch or work engaging member.

Referring to the drawing, the numeral 10 designates generally a block of suitable size and configuration which is adapted to be secured, as by bolts 13 or the like, to a punching mechanism, the block 10 being provided with a plurality of holes 11 through which the bolts 13 are adapted to pass. The block 10 is provided in substantially the center thereof with an opening 12 in which a work engaging member, generally designated as 14, is adapted to engage. The block

10 is also provided with a second opening 15 disposed laterally of the opening 12 and communicating therewith through a keyway opening 16.

A second lateral opening 17 is disposed in the block 10 and communicates directly with the opening 12 at a point spaced circumferentially from the opening 15. In the present instance, the second lateral opening 17 is disposed substantially 90° from the first lateral opening 15 10 but I, of course, do not wish to be limited to the particular spacing between these two openings 15 and 17.

The work engaging member 14, in the present instance, is disclosed as a punch but it will be understood that this work engaging member 14 may, if desired, be constructed in the form of a button die or the like, which is provided with the usual opening or recess to receive the operating end of the punch. The work engaging member 14 has a shank 18 engaging within the opening 12 and this shank 18 is provided with a plurality of threads 19 which extend partially about the peripheral surface of the shank 18, the purpose for which will be hereinafter described. 20 The shank 18 is also provided with a longitudinally extending keyway 20 which intersects the threads 19 and when the shank 18 is in locked or operative position, the keyway 20 is adapted to be disposed in confronting position to the 30 opening 17.

A key 21 carried by a substantially cylindrical body 22 is adapted to engage in the keyway 16 of the block 10 and is provided with teeth 23 engageable in the threads 19. The body 22 is 35 adapted to engage in the first lateral opening 15 and preferably this opening 15 opens through the inner or upper face of the block 10 as does the opening 17.

A spring or compressible locking member 24 is 40 disposed in the opening 17 and is of a size such that a portion thereof will project into the opening 12 so that when the shank 18 is in locked or operative position, the inner or projecting portion of the spring or locking member 24 will be 45 disposed in the keyway 20.

In the use and operation of this retaining means the block 10 is secured to the desired portion of the punching machine by the bolts 13. The shank 18 is provided on the peripheral surface thereof with a knurled portion 25 which facilitates the holding of the shank during the placement or removal thereof from the block 10. Initially, the shank 18 is so disposed that the keyway 20 will align with the teeth 23 carried by 55

the key 21. The shank 18 may then be freely moved inwardly of the block 10 and by reason of the tapered or reduced inner end portion 26 of the shank 18, the spring or yieldable locking member 24 will be compressed or reduced in size within the opening 17. When the keyway 20 alines with the teeth 23 of the key 21, the side of the shank 18 alining with the locking member 24 will present a smooth or unthreaded surface to 10 the spring 24 so that the compression of the spring 24 will be such as to reduce the diameter of this spring, rather than to compress the spring longitudinally. When the shank 18 is substantially entirely within the block 10 and the spring 15 24 is reduced in diameter, the shank 18 may be rotated substantially a quarter turn so that the threads 19 will force the inner end of the shank 18 against the adjacent face of the punching mechanism. Upon rotation of the shank 18 20 through substantially one-quarter turn, the keyway 20 will be disposed in a position confronting the opening 17, so that the spring 24 may expand and have a portion thereof projecting into the keyway 20 and thus yieldably hold the shank 18 25 against turning. The work engaging member 14 may then be used in the conventional manner and when it is desired to remove the member 14 from the block 10, the shank 18 is turned in a reverse direction so as to again compress the 30 spring 24 and move the keyway 20 to a position registering with the toothed key 21. When the shank 18 has the keyway 20 thereof registering with the toothed key 21, the shank 18 may be moved outwardly of the block 10. 35 It is, of course, understood that various changes and modifications may be made in the details of construction and design of the above specifically

described embodiment of this invention without departing from the spirit thereof, such changes and modifications being restricted only by the scope of the following claims.

I claim:—

1. In a punching means, a block provided with an opening to receive a work engaging member and provided with a pair of spaced apart openings communicating with said first opening, a work engaging member positionable in said first opening, threads carried by said member extending partially about the circumference thereof and terminating in the periphery of said member, said member also having a longitudinally disposed keyway intersecting said threads, a key disposed in 15 one of said pair of openings provided with teeth engageable in said threads, and a helical spring in the other of said pair of openings having a portion thereof projecting into said first opening to thereby engage in said keyway to hold said 20 member against turning.

2. In a punching means, a block provided with an opening to receive a work engaging member and provided with a pair of spaced apart openings communicating with said first opening, a 25 work engaging member disposed in said first opening, threads carried by said member extending partially about the circumference thereof and terminating in the periphery of said member, a toothed key engaging in one of said pair of open- 30 ings, said member having a longitudinally disposed keyway intersecting said threads, and a helical spring disposed in the other of said pair of openings and engageable in the keyway to yieldably hold said work engaging member against 35 turning within the block.

FERDINAND ZIGANEK.
